UNITED STATES PATENT OFFICE.

EMANUEL JACOBS, OF DETROIT, MICHIGAN.

RAZOR-SHARPENING DEVICE.

1,386,001.

Specification of Letters Patent.

Patented Aug. 2, 1921.

Application filed October 17, 1918. Serial No. 258,550.

To all whom it may concern:

Be it known that I, EMANUEL JACOBS, a citizen of the United States of America, residing at Detroit, in the county of Wayne 5 and State of Michigan, have invented certain new and useful Improvements in Razor-Sharpening Devices, of which the following is a specification, reference being had therein to the accompanying drawings.

The primary object of my invention is to provide a simple, durable and inexpensive razor honing device that may be expeditiously manipulated to provide a razor 15 blade with a sharp uniform edge, the device being particularly designed for sharpening a fixed single edge blade in contradistinction to the single or double edged detachable blades adapted for safety razors.

Another object of my invention is to provide a razor sharpening device that may be attached to a suitable support, held in the hand or otherwise supported during the 20 operation of sharpening a blade placed in position on the device, the blade being held by a novel holder that permits of a razor being properly positioned in the device to be sharpened.

A further object of my invention is to furnish a device of the character described with a novel reciprocatory and oscillatory sharpening element that may be manually reciprocated on the side of a blade and then readily transferred to the opposite side, this 25 being accomplished without disturbing the blade holder or the razor held thereby. The reciprocatory and oscillatory sharpening element is capable of vertical adjustment and in consequence thereof it is possible to provide the edge of a razor blade with a desired cutting edge.

My invention will be hereinafter specifically described and then claimed, and reference will now be had to the drawing, 30 wherein—

Figure 1 is a perspective view of the razor honing device, and

Fig. 2 is a vertical sectional view, showing an inactive position of the blade holder 35 by dot and dash lines.

In the drawing, the reference numeral 1 denotes a support or hand grip having slotted, opposed members 2 at the ends of

said support, said hand grip being slotted, as at 3, so that it may be held in one hand, 55 so as to reduce the weight of said support, and so as to provide clearance for a clip 4 slidable on said support.

The slotted support 1 and the slotted members 2 may be formed from sheet metal 60 to provide a rigid frame, and at one end of the support 1 is an interiorly screw-threaded boss or sleeve 5 that permits of the support being attached to any form of handle or a permanent support. 65

Pivottally connected to the support 1, intermediate the ends thereof, by a screw 6 or other pivotal means, is a blade holder 7, which in an active position is disposed longitudinally on the support 1 and in an 70 inactive position is swung at a right angle to said support so that a razor blade 8 may be easily placed in said holder. The blade holder is preferably in the form of a bar having side plates and these plates possess a degree of resiliency as to permit of the razor blade 8 being frictionally held between said side plates. By placing the outer end of the blade 8 at the end of the holder said blade may be slid into the 80

holder, and to provide clearance for the shank of the blade or the handle of the razor, one of the slotted members 2 has its side edge recessed, as at 9. With the shank of the blade 8 in the recess 9, the position 85 of the blade holder is defined on the support 1 and the clip 4 may be shifted to engage the sides of the blade holder, as shown in Fig. 1, and thus prevent an accidental pivotal movement of said blade 90 holder. The slotted support 1 is of sufficient length to accommodate the clip 4 at either end thereof, so that said clip will provide clearance for a swinging movement of the blade holder. 95

Adjustable in the slotted members 2 is a rod 10 having the ends thereof screw-threaded and provided with winged thumb nuts 11 that may be tightened against the outer faces of the members 2 to hold the 100 rod 11 in an adjusted position relative to the support 1; the slots of the members 2 being of a sufficient length to permit of the rod 10 being raised and lowered relative to said support. One end of the rod 105 10 may have a collar 12 to bind against

the inner face of one of the slotted members 2 and as an equivalent of this collar the rod 10 may be provided with a long sleeve that may be clamped between the 5 slotted members 2. The rod 10 is made adjustable relative to the members 2 so that it may be placed at an angle with respect to a razor blade, that is, with one end closer to the blade than the opposite end, 10 and thus cause any reciprocable sharpening device on said rod to shift on either side of the blade in an angular direction to the razor edge, during reciprocable movement of the sharpening device. The advantage 15 gained by this arrangement is that of preventing a ridge being formed on the sharpening device, and a wiping action obtained relative to the razor which is whetted and more thoroughly sharpened.

20 Slidable on the rod 10, between the slotted members 2, is a sleeve or hub portion 13 of a reciprocatory and oscillatory sharpening device 14, said device having the upper end thereof terminating in a finger piece 15 and the lower end thereof shaped to clamp a sharpening element 16, which may be detachably held in engagement with the device by transverse screw bolts 18 and winged thumb nuts 19. The sharpening element 16 25 may be in the form of a stone, piece of carbide, or any sharpening or dressing material and when positioned in the device between the screw bolts 18, it can be firmly held to bear against the sides of the razor 30 blade 8 as the sharpening device is reciprocated on the rod 10. The sharpening device is of such size, that it may be rocked or oscillated, at the end of the blade holder 7, so 35 that the sharpening element 16 may be shifted 40 from one side of the blade to the opposite side thereof, without adjusting the blade holder 7 on the support 1.

The sharpening device may be easily removed by detaching the rod 10 and sliding 45 the device off of one end of the rod, but such detachment is ordinarily not necessary as the entire device may be readily maintained in a sanitary condition.

It is thought that the manner of manipulating the device to sharpen a blade will be 50 apparent without further description, and while in the drawing there is illustrated the preferred embodiment of my invention, it is to be understood that the structural elements are susceptible to such variations and modification as fall within the scope of the 55 appended claims.

What I claim is:—

1. Means for honing a blade comprising a 60 blade holder adapted to support a blade with its edge exposed, a reciprocable blade sharpener having flat walls adapted to be alternately placed against the opposite walls of the blade and moved longitudinally thereof, 65 and means in the same plane as said blade

holder and confronting the edge of said blade and supporting said reciprocable blade sharpener against either wall of the blade in said holder, said means being disposed at an angle to said blade holder permitting of 70 said reciprocable blade sharpener being reciprocated and during such movement causing the end of said reciprocable blade sharpener to move at an angle relative to the exposed edge of the blade. 75

2. Honing means as characterized in claim 1 wherein the last mentioned means includes a rod either end of which may be adjusted to place said rod at an angle to the exposed 80 edge of the blade.

3. A razor sharpening device comprising a support, a pivoted blade holder on said support, a reciprocatory and oscillatory blade sharpener above said blade holder and adapted to be moved against the side of a 85 blade in said blade holder and shifted from one side of said blade to the other when at either end of the blade, and means carried by said support adapted to hold said blade holder in alignment therewith. 90

4. Means for sharpening a razor, comprising spaced members one of which is adapted to have a razor extend therethrough to a position between said members, a rod adjustably mounted in said members, a reciprocatory and oscillatory blade sharpener on said rod adapted to be shifted under said rod from one side of the razor to the other side when at either end of the razor blade and move longitudinally of either side when 100 reciprocated, and means between said members for holding the razor during the operation of said blade sharpener. 105

5. A razor sharpening device, comprising spaced members, a rod adjustably mounted 110 between said members, a reciprocatory blade sharpener supported by said rod adapted to be shifted from one side of the razor to the other side and moved longitudinally of either side, and means supported between 115 said members in proximity to said rod and adapted for holding a razor blade, said means being in spaced relation to said members so that said blade sharpener may be moved at the ends of the razor from one side thereof to the other.

6. Means for sharpening a razor comprising a support, a pivoted blade holder on said support, a clip slidable on said support adapted to engage the sides of said blade holder and maintain said blade holder in an active position, a sharpening element adjacent said support, and adapted to be shifted back and forth against either side of a blade in said holder, and adjustable means for 120 supporting said sharpening element so that it may be moved to and from the blade. 125

7. Means for sharpening a blade comprising a slotted support, a pivoted blade holder on said support, a slidable clip on said sup- 130

port adapted for holding said pivoted blade holder in an active position, slotted members at the ends of said support, a rod adjustable in said members, a reciprocatory and oscillatory member on said rod, and means adapted for holding a blade sharpening element in said reciprocatory and oscillatory member so that said member may be manipulated

to move said sharpening element back and forth on either side of said blade.

In testimony whereof I affix my signature in the presence of two witnesses.

EMANUEL JACOBS.
